UNITED STATES PATENT OFFICE.

LOUIS C. WEICHMAN, OF YOUNGSTOWN, OHIO.

COLLAR-CLIP.

1,139,452.

Specification of Letters Patent.

Patented May 11, 1915.

Application filed February 12, 1913. Serial No. 742,009.

To all whom it may concern:

Be it known that I, LOUIS C. WEICHMAN, a citizen of the United States, residing at Youngstown, in the county of Mahoning and State of Ohio, have invented certain new and useful Improvements in Collar-Clips, of which the following is a specification.

My invention relates to a collar clip or holder and has particular reference to a device of this character adapted to be passed through the back button holes of a shirt band and collar.

The invention aims to provide a clip or device of the above mentioned character, which will lie perfectly flat, may be used in connection with shirts and collars having back button holes of different sizes, will at all times prevent the collar from becoming accidentally unfastened, will be easy to use, and will be completely concealed by the ordinary double fold turned down collar.

In the accompanying drawings forming a part of this specification and in which like numerals are employed to designate like parts throughout the same, Figure 1 is a side view of a portion of a shirt band showing the clip arranged therein, Fig. 2 is a transverse vertical sectional view through the clip, showing the same holding a collar upon the shirt band, Fig. 3 is a plan view of the clip removed, and, Fig. 4 is a perspective view of the same.

In the drawings, wherein is illustrated a preferred embodiment of my invention, the numeral 5 designates a portion of a shirt provided with the usual band 6. This shirt band has its outer fold 7, at the back portion of said shirt, provided with a horizontally arranged opening or button-hole 8, as shown.

The numeral 9 designates the ordinary double fold turned down collar, provided with a horizontal button-hole 9^a, and surrounds the collar band in the usual manner.

My clip or holder comprises a horizontally arranged body portion or elongated plate 10, which is curved longitudinally in a horizontal plane, to conform generally to the curvature of the shirt band and collar, whereby the same will lie perfectly flat within the shirt band. Depending from the body portion 10 and equidistantly spaced from the ends thereof, is an L-shaped portion comprising a relatively short shank 11, which is vertically inclined or disposed at

an angle with relation to the horizontal body portion, as shown. Formed upon the free or lower end of the relatively short shank 11 is a horizontal or elongated head 12, forming the horizontal arm of the L-shaped portion which extends laterally beyond the shank 11 in one direction only in the plane of the shank 11 and in a plane substantially parallel to one end portion of the horizontal body portion or elongated plate 10. This is considered to be one of the most important features of the invention, as by reason of this construction the horizontal head 12 may be made quite long or in any desired length and can be inserted into and removed from the back button-hole 9^a of the collar 9. It is obvious that when the button-hole 9^a is large, the clip must be provided with a correspondingly long horizontal head 12. If the head 12 extended laterally beyond the shank 11 in both directions, it is obvious that the head could only be constructed relatively short, for if the same were too long it could not be passed through the button-hole of the collar. I have found that satisfactory results are obtainable by having the horizontal head 12 substantially co-extensive in length with the corresponding arm of the body portion 10, or a little longer. The horizontal head 12 is curved longitudinally in the horizontal plane, to conform generally to the curvature of the collar and when the clip is in use, such head is disposed in a vertical plane outwardly of the plane occupied by the horizontal body portion 10. All parts of the clip are preferably formed integral, the same being preferably stamped from a section of suitably thin and stiff sheet metal, or the like.

The clip when made of sheet metal is preferably plated with silver or gold, or the same may be made of any desired precious metal, celluloid or other suitable material.

In the use of the clip, the horizontal head 12 is first passed through the button-hole 8, to be disposed outwardly of the shirt band 6, as clearly shown in Fig. 1. The collar is then manipulated so that the horizontal head is passed through the button-hole 9^a, as shown in Fig. 2. The collar 9 will completely conceal the clip. It is obvious that the width of the horizontal head 12 must be of proper size to allow the head to be passed through the smallest button-hole in connection with which the clip is to be used. As the head extends laterally in one direction

only with relation to the depending shank 11, the same may be constructed sufficiently long, as shown in Fig. 1, whereby the same may be used in connection with almost any 5 collar which is now upon the market. The function in having the shank 11 relatively short, is to conceal the clip behind the collar. The function in having the shank 11 vertically inclined or angularly arranged 10 with relation to the body portion 10, is to have the head 12 disposed in a vertical plane outwardly of the body portion, when the clip is in use, whereby such head will not clamp against the outer surface of the collar 15 band and render it difficult to pass the head through the button-hole of a collar.

It is to be understood that the form of my invention herewith shown and described is to be taken as a preferred example of the 20 same, and that certain changes in the shape, size and arrangement of parts may be resorted to without departing from the spirit of the invention or the scope of the subjoined claim.

Having thus fully described my invention, 25 I claim:—

A substantially flat integral sheet metal collar button, comprising an upper body-

plate curved slightly longitudinally to conform to the curvature of a collar when arranged substantially horizontally; a depending shank integral with the lower edge of the body plate at a point substantially equidistantly spaced from the opposite ends thereof and vertically inclined outwardly and downwardly with respect to the body plate; and a relatively long head integral with the lower outer end of the depending shank, said head being spaced vertically a substantial distance from the body plate and curved slightly longitudinally to be substantially concentric with the curved body plate and conform to the curvature of the collar, said head extending in one direction laterally beyond the shank and longitudinally of the body plate, and the opposite end of the head terminating with the contiguous vertical edge of the shank to be flush therewith.

In testimony whereof I affix my signature 50 in presence of two witnesses.

LOUIS C. WEICHMAN.
